UNITED STATES PATENT OFFICE.

CORNELIUS G. MORROW AND SHERMAN H. OAKES, OF THOMASVILLE, NORTH CAROLINA.

DESIGN FOR A COMBINED WARDROBE AND DRESSER.

Application filed January 31, 1927. Serial No. 20,566. Term of patent 7 years.

To all whom it may concern:

Be it known that we, CORNELIUS G. MORROW and SHERMAN H. OAKES, citizens of the United States, residing at Thomasville, in the county of Davidson and State of North Carolina, have invented a new, original, and ornamental Design for a Combined Wardrobe and Dresser, of which the following is a specification, reference being had to the accompanying drawing, forming part thereof.

The figure is a perspective view of a combined wardrobe and dresser showing our new design.

We claim:

The ornamental design for a combined wardrobe and dresser, as shown.

CORNELIUS G. MORROW.
SHERMAN H. OAKES.
